FIG. 1 is an isometric view of an oral irrigator handle with a tip shown in dashed lines for environment.

FIG. 2 is a front isometric view of the oral irrigator handle of FIG. 1.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken line showing of the tip in FIG. 1 illustrates environment and forms no part of the claimed design. The other broken lines in FIGS. 1–8 indicate features of the oral irrigator handle that form no part of the claimed design.
